(57) **CLAIM**

The ornamental design for a keyboard with cover and stand for electronic device, as shown and described.

DESCRIPTION

Keyboard with cover and stand for electronic device

1.1 : Front view

1.2 : Back view

1.3 : Left view

1.4 : Right view

1.5 : Top view

1.6 : Bottom view

1.7 : Perspective view

1.8 : Front view of folded state

1.9 : Left view of folded state

1.10 : Top view of folded state

1.11 : Front view of component 1

1.12 : Back view of component 1

1.13 : Left view of component 1

1.14 : Right view of component 1

1.15 : Top view of component 1

1.16 : Bottom view of component 1

1.17 : Front, left side perspective view of component 1

1.18 : Bottom, right side perspective view of component 1

1.19 : Front view of folded state of component 1

1.20 : Left view of folded state of component 1

1.21 : Top view of folded state of component 1

1.22 : Front view of component 2

1.23 : Back view of component 2

1.24 : Left view of component 2

1.25 : Right view of component 2

1.26 : Top view of component 2

1.27 : Bottom view of component 2

1.28 : Front perspective view of component 2

(Continued)

1.29 : Back perspective view of component 2
 1.30 : Right view of unfolding state of component 2
 1.31 : Top view of unfolding state of component 2
 The broken lines shown in the drawings illustrate portions of the keyboard with cover and stand for electronic device that form no part of the claimed design; the dash-dot broken lines illustrate the boundary of the claimed design and form no part thereof; the component 2 discloses a small stand that can be taken out of the product and used alone to support the electronic device; the component 1 shows the claim without the small stand.

1 Claim, 31 Drawing Sheets
